CLAIM

The ornamental design for an elongated medical device with flexibility enhancing features, as shown and described.

DESCRIPTION

FIG. 1 is a perspective view of an elongated medical device with flexibility enhancing features showing our new design; FIG. 2 is a first side elevational view of the elongated medical device; FIG. 3 is a second side elevational view of the elongated medical device; FIG. 4 is a third side elevational view of the elongated medical device; FIG. 5 is a fourth side elevational view of the elongated medical device; FIG. 6 is a distal end view of the elongated medical device; and, FIG. 7 is a proximal end view of the elongated medical device. The broken lines illustrate unclaimed portions and form no part of the claimed design.
